(57) **CLAIM**

The ornamental design for an electronic housing, as shown and described.

DESCRIPTION

FIG. 1 depicts a perspective view of an electronic housing in accordance with an embodiment;

FIG. 2 depicts a front view thereof;

FIG. 3 depicts a back view thereof;

FIG. 4 depicts a right view thereof;

FIG. 5 depicts a left view thereof;

FIG. 6 depicts a top view thereof;

FIG. 7 depicts a bottom view thereof; and,

FIG. 8 depicts a cross-sectional view taken across line 8-8, as shown in FIG. 6.

The oblique shade lines in the Figures indicate transparent or semi-transparent surfaces and not surface ornamentation. The broken lines in the drawings illustrate features of the electronic housing that form no part of the claimed design.
